UNITED STATES PATENT OFFICE.

FREDERICK S. DENISON, OF MINNEAPOLIS, MINNESOTA, ASSIGNOR TO MINNEAPOLIS
HEAT REGULATOR COMPANY, OF MINNEAPOLIS, MINNESOTA, A CORPORATION.

THERMO CIRCUIT-CLOSER.

1,290,928.

Specification of Letters Patent. Patented Jan. 14, 1919.

Application filed May 3, 1917. Serial No. 166,240.

To all whom it may concern:

Be it known that I, FREDERICK S. DENISON, a citizen of the United States, resident of Minneapolis, county of Hennepin, State 5 of Minnesota, have invented certain new and useful Improvements in Thermo Circuit-Closers, of which the following is a specification.

In the operation of a thermostatic device 10 for controlling the dampers of a heating apparatus, difficulty has been experienced in preventing the thermostatic bar from becoming bent or twisted out of proper shape through the pressure on the rigid contact 15 screws of the terminals. The object, therefore, of my invention is to provide an improved means for mounting these contact screws in such a manner that they will accommodate themselves to the pressure of the 20 thermostatic bar without interfering with the closing of the circuits therethrough.

The invention consists generally in various constructions and combinations, all as hereinafter described and particularly 25 pointed out in the claims.

In the accompanying drawings forming part of this specification,

Figure 1 is a front view, partially in section, of a thermostat embodying my invention,

Fig. 2 is a vertical sectional view of the same,

Fig. 3 is a front view of the gage with a portion of the dial broken away, showing 35 the application of my invention thereto.

In the drawing, 2 represents the base of a thermostat. 3 is a thermostatic bar, having a tongue 4 which projects downwardly between contact screws 5 which are mounted 40 in posts 6. The bar 3 has a conductor A leading to one terminal of a motor B and the posts 6 have conductors C and D leading therefrom to the motor. 7 is an indicator hand pivoted at 8 on the base and movable 45 over the graduations of a dial 9. The posts 6 are mounted in links 10 which are pivoted at 11 on the indicator 7 on each side of its pivot 8 and are pressed inwardly toward each other and a stop 12 by means of springs 50 13. These springs are comparatively light and are adapted to yield under pressure of the thermostatic bar on the contact screws, so that, if the instrument be set for a high 55 temperature and for some reason the room should become cold so that the bar is con-

tracted and would normally bear without undue pressure upon one of the contact screws, the spring for the link on which said screw is mounted would allow the link to swing outwardly while still remaining in 60 contact with the bar until the temperature rose sufficiently to expand the bar and move it in the opposite direction.

In Fig. 3 the invention is applied to a gage 14 having the usual hollow coil 15 connected with the coupling 16 through which pressure is admitted to the coil. One end of this coil has a tongue 17 thereon to extend between the contact screws, as described, and a link 18 connects said end with 70 a quadrant 19 which is geared in any suitable manner to the indicator hand 20 that is movable over the face of the dial 21. The contact screws and the links are substantially the same as described with reference 75 to Fig. 1 and I will designate them by the same reference numerals.

With this manner of mounting the contact screws there will be no danger of bending or twisting the thermostatic bar or the 80 hollow coil, even though there should be considerable range in the expansion and contraction of the coil.

I claim as my invention:

1. A circuit closer comprising a base, a 85 thermostatic member mounted thereon, a pivoted indicator hand, links pivoted at one end on said indicator hand near its pivot for oscillation therewith upon opposite sides of said thermostatic member, contact screws 90 carried by said links and mounted in the path of said member to be engaged and actuated thereby, springs for yieldingly resisting the pressure of said thermostatic member on said screws, an electric circuit 95 connected with said member and with said screws and closed by the contact of said member with said screws.

2. A circuit closer comprising a base, a thermostatic member mounted thereon, a 100 pivoted indicator, contact screws pivotally supported by said indicator upon opposite sides of said thermostatic member and in the path of the same, said screws being mounted to yield under pressure of the thermostatic 105 member thereon, an electric circuit connected with said member and with said screws and closed by the contact of said member with said screws.

3. A circuit closer comprising a base, a 110

thermostatic bar mounted thereon and having a depending end, an indicator hand pivoted on said base beneath said bar, links pivoted on said indicator hand upon opposite sides of said bar and springs for normally holding said links toward each other with a yielding pressure, contact screws mounted on said links in the path of the depending end of said bar, an electric circuit connected with said bar and with said screws and closed by the contact of said bar with said screws.

4. A circuit closer comprising a base, a thermostatic bar mounted thereon and having a depending end, an indicator hand pivoted on said base, links pivoted at one end on said hand, springs mounted at one end on said indicator hand and bearing at their opposite ends on said links for pressing them together, contact screws carried by said

links upon opposite sides of and in the path of the depending end of said bar, said links and screws oscillating on said indicator hand under pressure of the thermostatic bar thereon, an electric circuit connected with said bar and with said screws and closed by the contact of said bar with said screws. 25

5. A circuit closer comprising a base, a thermostatic member mounted thereon, a pivoted indicator hand, links pivoted on said indicator hand and mounted to yieldingly resist the pressure of said thermostatic member, contact screws carried by said links in the path of said member, and an electric circuit connected with said member and with said screws and closed by the contact of said member with said screws. 30 35

In witness whereof, I have hereunto set my hand this 23rd day of April, 1917.

FREDERICK S. DENISON.
